No. 769,849.

PATENTED SEPT. 13, 1904.

W. B. TERRY.

COMBINATION MEASURING INSTRUMENT.

APPLICATION FILED DEG. 3, 1903.

NO MODEL.

UNITED STATES PATENT OFFICE.

WILLIAM BLAKE TERRY, OF ASPERMONT, TEXAS.

COMBINATION MEASURING INSTRUMENT.

SPECIFICATION forming part of Letters Patent No. 769,849, dated September 13, 1904.

Application filed December 3, 1903. Serial No. 183,651. (No model.)

To all whom it may concern:

Be it known that I, WILLIAM BLAKE TERRY, a citizen of the United States, residing at Aspermont, in the county of Stonewall and State 5 of Texas, have invented certain new and useful Improvements in Combination Measuring Instruments; and I do declare the following to be a full, clear, and exact description of the invention, such as will enable others skilled in the 10 art to which it appertains to make and use the same.

This invention relates to improvements in measuring instruments.

The object of the invention is to provide an 15 instrument having a wide range of usefulness in measuring, leveling, and surveying operations and so constructed as to be of advantage to mechanics and workmen of different callings.

In the accompanying drawings, Figure 1 is a 20 side view of one side of the combination instrument, showing in dotted lines the extended positions of the parts. Fig. 2 is a similar view of the opposite side. Fig. 3 is an edge view. Fig. 4 is a detail sectional view on the line 25 4 4 of Fig. 1. Fig. 5 is a similar view on the line 5 5 of Fig. 1. Fig. 6 is a detail fragmentary sectional view on the line 6 6 of Fig. 1.

Referring to the drawings more particularly, 1 denotes a square, the arms or blades 30 2 and 3 of which are of equal length and are each, preferably though not necessarily, two feet in length and of suitable width and thickness. The arms or blades of the square are formed with an inner core 4, of wood, which 35 is inclosed in a metallic casing 5, constructed in two sections to permit the same to be applied to the wooden core, said sections being held in place by screws or other fastening devices 6. Between the adjacent ends of the 40 outer side edges of the casing a space is left to form a groove or channel 7, the purpose of which will be hereinafter described. Connecting the ends of the arms is a curved blade or segment 8, which is so constructed as to be 45 extended beyond the arms or blades 2 and 3, as shown in dotted lines in Fig. 1. The segmental blade 8 consists of a central body portion 9, which is substantially H-shaped in cross-section and provided with projecting 50 side flanges 10, which are adapted to be en-

gaged by casings 12 and 13, said casings being arranged on the flanged sides 10 to slide in opposite directions. Set-screws 14 are provided near the ends of the casings 12 to engage the body portion 9 and hold said casings 55 extended to any desired position. The body portion 9 of the segmental blade may be secured to the ends of the arms or blades 2 and 3 in any suitable manner, but are here shown as provided with a screw-bolt 15, which is 60 passed through the ends of the body portion 9 radially and through openings in the ends of the arms or blades 2 and 3, where they are adapted to engage nuts 16, which are countersunk or inserted in openings therefor in the 65 sides of said arms or blades.

To one end of the sliding casing 12 is connected the outer end of an arm or brace-bar 17, and to the opposite end of the casing 13 is connected the outer end of an arm or brace-bar 18. The inner ends of the arms or brace-bars 17 and 18 are pivotally connected and mounted in the corner of the connected ends of the square. The brace-bars 17 and 18 are of such width that they are adapted when 75 folded to lie within the grooves or channels 7 between the edges of the casings 5.

In one side of the body or core 4 are formed a number of recesses, in which are arranged instruments of different varieties, and in the 80 casing 5 over said recesses are formed view-openings, whereby the instruments may be read.

Near the upper end of the blade 2 is formed a recess, in which is arranged a transversely-disposed spirit-level glass 20. Immediately below the spirit-level 20 is arranged an opening through the blade, and in said opening is arranged an altitude-gage 21. Below the altitude-gage is arranged in the side of the blade 90 a thermometer 22, on a line with which, but in the inner edge of the blade, is arranged a vertically-disposed spirit-level glass 23. Below the thermometer 22 and level 23 is arranged a barometer 24.

Near the lower end of the blade 2 is arranged a plumb-level 25, consisting of a dial on which is arranged radially-disposed degree-marks. In the center of the dial is pivoted a pendulum 26, which when the blade 2 is in an exactly 100

perpendicular position will register at "0," but when the blade or square is leaned in one direction or the other the degrees of such inclination will be indicated by the pendulum on 5 the dial.

Near the outer end of the arm or blade 3 and in the side of the same is arranged a vertically-disposed spirit-level glass 27, while substantially midway between the ends of the 10 blade and in the edge of the same is arranged a horizontally-disposed spirit-level glass 28. Near the inner end of the blade 3 and on the side of the same is arranged a socket 29 for the reception of a Jacob's staff.

15 On the edge of the blade 3 and at the inner end or corner of the same is mounted a surveyor's rear sight-piece 30, which is adapted to have a sliding engagement in a socket 31, formed on the blade, whereby the same may 20 be pushed in when not in use. A front sight-piece 32 is arranged near the outer end of the arm 3 to coat with the sight 30 and form a leveling or surveying instrument. The sight-piece 32 is formed in the shape of a spring- 25 plate, one end of which is fixed to the edge of the blade by a screw or other suitable means, this sight being normally held down against the blade by a slide 33.

When the instrument is to be used for surveying or leveling purposes, the same is inverted to bring the outer edge of the blade 3 up in a horizontal position. A Jacob's staff is then inserted in the socket 29 to support the instrument and the sight-pieces elevated for 35 use. On the outer edge of the blade 3 is removably secured a mariner's compass 34 and oppositely-arranged spirit-levels 35 and 36, all of which are used in connection with the sights 30 and 32 to facilitate the leveling and surveying operations when the instrument is used for 40 this purpose.

It will be understood that the compass 34 and levels 35 and 36 will be removed when the segmental casing is to be extended to permit 45 the arm or bar 18 to swing outwardly.

The slideable members 12 13 of the blade or segment 8 enable the arms or bars 17 18 to be disposed at any desired angle to enable the instrument to be used when placing timbers at 50 any inclination or at angles other than right angles.

On the sides of the casings of the blades 2 and 3 opposite to that containing the recesses is arranged the ordinary division-marks indicating inches and fractions of inches. On the sliding casings 12 and 13 are formed two sets of division-marks, indicating both inches and degrees, as shown.

The many uses in which this instrument 60 may be employed and the advantages to be had by arranging in combination the various useful instruments herein described will be readily apparent from the foregoing description taken in connection with the accompanying drawings.

Various changes in the form, proportion, and the minor details of construction may be resorted to without departing from the principle or sacrificing any of the advantages of 70 this invention.

Having thus described my invention, what I claim, and desire to secure by Letters Patent, is—

1. An instrument of the class described, comprising a square, and a segmental blade 75 connecting the outer ends of the arms of the square and having slideable members adapted to be extended beyond the said arms.

2. An instrument of the class described, comprising a square, a segmental core-piece 80 connecting the outer ends of the arms thereof, and segmental casings slidably secured on the said core-piece and thereby adapted to be extended in opposite directions beyond the said arms.

3. An instrument of the character described, consisting of a square, measuring instruments arranged on and carried by the blades of said square, a segmental blade consisting of a central body portion, removably 90 secured to and connecting said square-blades, and oppositely-sliding side pieces mounted on said central portion, having means for slidably holding said side pieces to said central piece and means for holding the same in 95 adjusted positions, substantially as described.

4. An instrument of the character described, consisting of a square, measuring instruments arranged on and carried by the blades of said square, a segmental blade consisting of a central flanged body portion removably secured to and connecting said square-blades, and side pieces slidably engaging said flanged central portion to move in opposite directions, brace-bars pivotally 100 connected at one end to said sliding side pieces and at their opposite ends to said square, and set-screws arranged to hold said sliding side pieces in their adjusted positions, substantially 105 as described.

5. An instrument of the character described, consisting of a square, the arms or blades of which are formed of an inner core or body portion, and an outer shell or casing, recesses formed in said inner core or body 115 portion to contain measuring instruments, view-openings formed in said casings over said recesses, a segmental blade consisting of a central flanged body portion, removably secured to and connecting said square-blades, and side pieces slidably engaging said flanged central portion to move in opposite directions, brace-bars pivotally connected at one end to said sliding side pieces and at their 120 opposite ends to said square, and set-screws arranged to hold said sliding side pieces in their adjusted positions, substantially as described.

6. An instrument of the class described, comprising a square, a segmental blade con- 125

necting the ends of the arms of the square and having slideable members adapted to be extended beyond the arms of the square, and arms attached to the ends of the said slideable members and pivotally connected to the square at the point where the arms thereof meet.

In testimony whereof I have hereunto set my hand in presence of two subscribing witnesses.

WILLIAM BLAKE TERRY.
